UNITED STATES PATENT OFFICE.

FRANK J. ANDERSON, OF BOX ELDER, MONTANA.

NAPKIN-HOLDER.

1,112,964.

Specification of Letters Patent.

Patented Oct. 6, 1914.

Application filed April 10, 1914. Serial No. 831,049.

To all whom it may concern:

Be it known that I, FRANK J. ANDERSON, a citizen of the United States, residing at

Box Elder, in the county of Chouteau, 5 State of Montana, have invented certain new and useful Improvements in Napkin-Holders; and I do hereby declare the following to be a full, clear, and exact description of the invention, such as will enable others skilled in the art to which it appertains to make and use the same.

This invention relates to improvements in napkin holders, and particularly to devices for holding napkins on the clothing.

15 The principal object of the invention is to provide a simple and novel device for clamping one corner of a napkin and having independent means for gripping the garment.

20 Other objects and advantages will be apparent from the following description, when taken in connection with the accompanying drawings.

In the drawings: Figure 1 is a perspective view of the napkin holder in operative position. Fig. 2 is a longitudinal sectional view through the device in the position shown in Fig. 1. Fig. 3 is a perspective view of the holder in open position.

25 Referring particularly to the accompanying drawings, 10 and 11 represent respectively the outer and inner plates of the holder. Connecting these plates at the ends thereof are the plates 12, these latter being 30 connected to the plates 10 and 11 by means of the spring hinged joints 13. These spring hinged joints have a tendency to normally throw the parts into trapezoidal form as shown in Fig. 1, the corner of the napkin 35 being arranged to be passed between the plates 10 and 11 and held by the collapsed portions of the device. One end of the outer plate is formed with a plurality of transverse teeth 15 which coöperate with 40 teeth 16 formed on a hinged member 17 carried by the adjacent end of the inner

plate 11. A coiled spring 18 is mounted on the pivot pin of the member 17 and bears against a finger-piece 19 formed integrally with the member 17, and forces the member 17 normally against the teeth 15. The adjacent portion of the plate 10 carries a thumb-piece 20 which is arranged to be grasped together with the thumb-piece 19 so that the member 17 can be swung on its pivot against the tension of the spring 18 and force the member away from the plate 10. A portion of the garment may then be inserted between the plate and member 17 and be firmly gripped therebetween when 55 the member 17 is released.

It will thus be seen that I have provided a simple and effective device for holding a corner of the napkin and at the same time suspending the same from a garment 60 to protect the clothing. The napkin may be folded or rolled and then inserted between the plates 10 and 11 in the manner of using a napkin ring, the device clasping on the napkin and holding the same firmly 70 therein.

What is claimed is:

A napkin holder comprising a pair of superposed plates, spring actuated members connecting the plates and holding the 75 plates normally in closed position to clamp a napkin normally therebetween, the projecting end of one plate being formed with garment engaging teeth, a pivoted spring-pressed tooth member carried by the other 80 plate for coöoperative engagement with the toothed end of the first plate to grip a portion of a garment and thumb-pieces carried by the first named plate and the pivoted tooth member. 85

In testimony whereof, I affix my signature, in the presence of two witnesses.

FRANK J. ANDERSON.

Witnesses:

NELLIE R. LARRON,
JOHN LARRON.
